ELECTROMECHANICAL OSCILLATOR

Noel Deisch, Washington, D. C.

Application June 13, 1929, Serial No. 370,666

8 Claims. (Cl. 250—36)

The invention relates to electromechanical oscillators, especially to means of drive therefor, and is a continuation in part of my copending application on Electromechanical oscillators filed

5 April 16, 1928, Serial Number 270,546.

The general purpose of the invention is to provide means by which the rate or frequency of vibration of the oscillator is rendered more nearly constant; its more restricted object, broadly stated, is to provide means by which the periodic force which drives the oscillator is automatically held in constant phase relation to the vibrations of the oscillator, and the value of this force automatically controlled in a way such that the 15 amplitude of vibration of the oscillator is held constant.

More specific objects relating to the construction, arrangement, and operation of the apparatus involved in carrying out the invention will 20 become apparent as the description proceeds.

Referring to the drawings;

Fig. 1 is a diagram showing a transparent, rod-shaped oscillator, an associated optical system by which the state of strain in the oscillator 25 is automatically determined at selected phases of the oscillator's vibration, light receptors or relays by which determinations of the state of strain in the oscillator as expressed in optical values are converted into corresponding electrical values, 30 and electrical circuits and other electrical apparatus by which driving energy is supplied to the oscillator, its amplitude of vibration controlled, and the phase relation of the driving force and of the oscillator vibrations maintained substantially 35 constant.

Fig. 2 is an enlarged view on the line 2—2 of Fig. 1, and shows the direction of incidence of the light beam and its path through the oscillator.

Fig. 3 is an enlarged fragmental view of the alternating current generator shown at 114 in Fig. 1, and shows means by which the angular position of the stator coils of the generator may be varied relatively to the field poles.

Figs. 4, 5 and 6 are fragmental views of the system illustrated in Fig. 1, and show, together with the corresponding portion of Fig. 1, a complete cycle of positions of the rotating mirror, during which the two light beams are directed into corresponding receptors at appropriate phases of the 50 vibration of the oscillator.

Fig. 7 is a diagram showing on a larger scale the angular disposition of certain optical elements of the apparatus illustrated in Figs. 1, 4, 5 and 6.

Fig. 8 is an enlarged perspective view of a type

of optical compensator shown diagrammatically at 24 in Fig. 1.

Fig. 9 is a diagram showing the preferred phase relation between the vibrations of the oscillator and the phases of the driving force.

Fig. 10 shows the effect on the ellipticity of the polarized light transmitted by the oscillator, produced by a displacement in opposite directions along the time axis of a group of corresponding phasal points in the vibration of the oscillator, 65 at which points optical determinations of the state of strain in the oscillator are made.

Fig. 11 shows two series of optical determinations of strain in the position which they retain when the rotating mirror is in phase synchronism 70 with the oscillations of the rod, the members of each series being located 360° apart on the time axis.

Fig. 12 shows the alteration in the positions of the two series of strain determinations shown 75 in Fig. 11, caused by a departure from phase synchronism.

Fig. 13 shows the positions of four series of optical determinations of strain, two of these series, 140, 141, situated on the line of zero displacement 80 and identical with those shown in Fig. 11, being used in fixing the phase position of the oscillator with reference to the driving force, and two additional series, 142, 143, situated at opposite crests 85 of vibration, being used in fixing the amplitude of vibration of the oscillator.

Fig. 14 shows a complete series of transformations from zero retardation to a retardation of one wave-length as they occur in elliptically polarized light as produced in the strained oscillator.

Fig. 15 shows transformations in the state of retardation of polarized light transmitted by the oscillator and the compensator at various phases of the motion of the oscillator under certain arbitrarily assumed conditions of vibration, the 95 sinusoidal curve 132 representing the magnitude of the strain in the rod plotted against time, and the series of circles and vertical and horizontal lines at the left of the figure the state of polarization of the emergent light at corresponding phases of the vibration of the oscillator.

Fig. 16 shows the saturation curve of a sample of iron such as might constitute the core 113 of the mutual inductance coil 111 of Fig. 1, and 105 illustrates the action of the amplitude governor.

One of the factors on which the constancy of period of an oscillator depends is the aggregate damping force acting on the oscillator, and since the forces tending to maintain a constant fre-

55 110

quency in an oscillating system vary inversely as the square of the damping coefficient, it is important that this coefficient be reduced to the lowest possible value.

- 5 An inharmonic application of the driving force may be an important source of damping, and it may be shown that, ideally, the driving energy should be communicated to the oscillator through the application of a force of sinusoidal character 10 held in the phase relation to the vibrations of the oscillator shown in Fig. 9, where the curve 132 represents successive positions of one of the constituent particles of the oscillator on either side of its position of rest (represented by the axis of 15 abscissae 133) and the curve 131 represents the alterations in the polarity and potential of the driving electromotive force (the axis of abscissae 133 here representing zero voltage) as plotted against time.
- 20 It will be seen by an inspection of this diagram that the curve representing the vibratory movement of the rod lags on the curve representing the driving electromotive force by 90°, the middle of the ventral segments of the one having the same 25 ordinate as the nodes of the other. The maximum value of the driving force occurs at the point of most rapid movement of the rod, the minimum algebraic value (which corresponds to the point of reversal of the polarity of the driving 30 force) taking place at the extremities of the period, when the rod is momentarily quiescent, that is, at the middle of a ventral segment. The ordinate of the driving force hence has its greatest algebraic value at a phase in the oscillation 35 of the rod when the constituent particles of the rod are moving at their highest rate, and has its least algebraic value at a phase when these particles are moving at their lowest rate.
- To achieve a constant rate the energy input 40 should be free from disturbances in value, the shape of the curve representing the driving force should remain constant, and the phase relation of this curve to the curve representing the rod vibrations should remain fixed.
- 45 The methods of drive hitherto employed in electro-mechanical oscillators fail to meet these exacting conditions. As respects the characteristics of the wave-form there is usually a wide departure from the ideal sinusoidal form just indicated. Each pulse of the driving current may 50 in fact be of such phasal length, or it may fall at such an epoch on the time axis, as to overlap two opposed phases of the rod's motion, thereby exerting a damping effect on the latter, and 55 though this damping effect will not be as great as the driving effect of the pulse, it will none the less introduce irregularities in the rate of the oscillator, and tend to set up oscillations in the latter which are harmonics of the fundamental 60 oscillation. The energy pulse may also suffer variations of amplitude due to the fatigue of batteries or other cause, or it may not be applied at the identical phasal position over long periods, notably through the fact that thermionic methods 65 of amplification as commonly used to effect a drive are very sensitive to disturbance by slight and often uncontrollable changes in the constants of the circuit.
- 70 Though the methods of drive hitherto used may afford a degree of constancy in the period of the oscillator ample for many purposes of laboratory investigation, it is essential, in cases where the highest attainable degree of precision over long 75 periods of time is the object, that the driving en-

ergy be applied and controlled in a way such as will satisfy the conditions above stated.

In this, as in my former application above referred to, the oscillator in its preferred form consists of an elastic rod 15, Fig. 1, supported at its nodal point, at 19, and oscillating freely along its longitudinal axis at its lowest natural frequency. In my former application a method was described by which the frequency of the output of the electrical oscillation generator which supplied driving energy to the oscillator was controlled by an electrostatic coupling between the rod and the oscillation generator. A coupling of this type necessarily adds to the external damping of the oscillator, and in the present invention this source of damping is entirely eliminated through the expedient of providing an optical coupling between the rod and the oscillation generator.

The physical principles underlying the method by which this optical coupling is established will now be set forth.

It is well known that a stressed transparent body acts toward polarized light in the same way as a birefringent crystal, its optical behavior being analogous to that of a negative crystal 100 when the body is in compression and to that of a positive crystal when in tension, the optical axis in each case being parallel to the direction of the applied force. An oscillating rod, then, in which there exists an alternate state of tensional and 105 compressional stress, is alternately positively and negatively birefringent, the effect being greatest at the nodal point of oscillation and decreasing progressively toward the ends of the rod, where it is zero. Since the optical effects of extension 110 and compression are opposite and proportional to stress, the degree of birefringent of the rod is a periodic function of the time, equal phases exhibiting equal double refraction.

Assuming a rod of adequate dimensions, and 115 vibrating at sufficient amplitude, the elliptically polarized light emergent from the rod under conditions to be described will for each quarter oscillation (half vibration) go through a cycle of complete transformations, changing through the 120 series,—plane polarized, elliptically polarized, circularly polarized, elliptically polarized, plane polarized, etc.—as diagrammed in Fig. 14, which shows a complete series of transformations from zero retardation to a retardation of one wave- 125 length, and in Fig. 15, which shows a number of complete transformations in apposition to the movement of the rod. (In the latter case the added retarding effect of a compensator is included, as explained hereafter.) Thus, if 113 130 Fig. 15 be the trace of the motion of the rod about the position of rest, represented by the axis of abscissae 133, then the state of polarization at the phase 144 will be as shown at 150, that is, the light will be circularly polarized. At the phase 135 145 the light will be polarized as at 156, that is, it will be polarized in a vertical plane, at the phase 146 the emergent light will be polarized as at 151, that is, circularly polarized, etc. In other words the series of transformations shown in more 140 detail in Fig. 14 will be successively passed through, and this series will be repeated until the position of greatest strain, represented in the case shown in Fig. 15 by the point 161 is reached. On the following quarter oscillation the series 145 will of course be traversed in reverse order. The same action takes place in the second half of the complete oscillation, that is, the part that lies below the axis of abscissae. The number of transformations shown is arbitrary, and will vary with 150

the material, with the dimensions of the rod, and with its amplitude of vibration.

The above facts relating to the optical properties of transparent rods in oscillation, in connection with the system of mechanical, optical, and electrical elements now to be described, by which the momentary phase position of the oscillator is fixed through an optical determination of its internal strain, form the basis of a method of establishing an optical coupling between the vibrating rod and the generator of an alternating E. M. F. which supplies driving energy to the rod in such way as to synchronize the motion of this generator with the vibrations of the rod.

Referring more particularly to Fig. 1, there is shown a source of radiation 1 and means such as a monochromator 2 for selecting a certain restricted region of the radiation produced by the source 1. This source may consist of a mercury vapor lamp, and the monochromator may comprise a conventional arrangement of parts such as the restricting slit 3, the collimator 4, the dispersing prism 5, the imaging lens 6, and the selecting slit 7. The transmitted radiation may for example be restricted to the line 4359A of the spectrum of mercury vapor. The beam emergent from the monochromator 2 is collimated by the lens 8 and falls on the half-metallized mirror 9, by which a large part of the beam is reflected at right angles and enters the polarizer 11, the cylindrical lens 13, the transparent oscillating rod 15, the cylindrical collimating lens 21, the compensator 23, the analyzer 26, and the imaging lens 36, which focuses it on successive facets of the rotating mirror 42. A second portion of the beam, which may be of substantially the same flux density as the first, is transmitted by the mirror 9 and falls upon the totally reflecting mirror 10, where it is reflected at right angles and passes through the analogous system comprising the polarizer 12, the cylindrical condensing lens 14, the oscillating rod 15, the cylindrical collimating lens 22, the compensator 24, the analyzer 27, the reflecting prism 41 by which it is in the illustrative construction bent through an angle of 67½°, and the imaging lens 39 which focuses it on successive facets of the rotating mirror 42.

The polarizers 11 and 12, and the analyzers 26 and 27, may consist of Nicol prisms, the construction of which is well known. The polarizers 11 and 12 are turned on their longitudinal axes through an azimuth of 45° with respect to the longitudinal axis of the rod 15, whereas the principal plane of the analyzers 26 and 27 is desirably but not necessarily held orthogonal with the axis of the rod, as shown. The cylindrical lenses 13, 21, and 14, 22, as shown in Fig. 2 are separated from each other by a distance equal to their combined focal length, and are so placed with respect to the oscillating rod that the axis of the latter coincides with the focal point of the lenses, to the end that the convergent and divergent beam is perpendicularly incident on the air-rod interface so that refraction in the rod does not occur and the paths of all of the elements of the beam within the rod are of equal length. The compensators 23 and 24, whose purpose is to restore an elliptical vibration to a rectilinear vibration, or to change a given elliptic vibration to an elliptic vibration of different ellipticity, may be of the Soleil-Babinet type shown in detail in Fig. 8, consisting of a plane parallel plate 122 made of some doubly refracting material such as quartz, whose optical axis may be taken as represented by the arrow 125,

and a split plane parallel plate composed of a wedge pair 123a and 123b also made of a doubly refracting material, and whose axes may be taken as represented by the arrows 126. The plate 123b is adapted to be displaced in the direction of the arrow 127 by means of a micrometer screw 25 (Fig. 1). The plate 122 is normally equal in its order to the wedge pair 123a, 123b at some intermediate thickness. The effective thickness of the wedge-pair may thus be varied, causing a continuous variation from positive to negative order in the transmitted polarized beam. The compensator 23 will normally be adjusted so that the polarized light incident on the analyzer 26 will be in the state of polarization shown at 150 in Fig. 15, that is, circularly polarized, when the rod is at rest, or when the instantaneous position of the particles of the vibrating rod is that shown by the intersection of the curve 132 with the axis 133 of Fig. 9. The adjustment of the second compensator 24 will depend on the conditions of operation, and will be described farther on.

From the above description it will be seen that light will be transmitted in different amounts by the analyzers 26 and 27 at different epochs of the vibration of the rod, being fully transmitted at the epochs corresponding to polarized light 157, 159, etc. of Fig. 15, half transmitted at epochs corresponding to polarized light 150, 151, etc., and extinguished at epochs corresponding to polarized light 156, 158 etc. There will result a series of transmissions of light through the analyzer 26 at each oscillation, or more correctly a series of fluctuations from zero, to maximum, to zero, etc., in the quantity of light transmitted by the analyzer, in accordance with the relative proportion of the two perpendicular components of the elliptically polarized monochromatic beam that at succeeding moments become incident on the analyzer. There is thus afforded a means of determining the state of strain in the oscillator at any phase of its vibration.

That portion of the light beams 30 and 52 (Fig. 1) passed by the analyzers 26 and 27 is, as above stated, focused on the faces of the rotating mirror 42 by the lenses 36 and 39, respectively. As this mirror, which normally rotates in synchronism with the rod vibrations, sweeps around through successive positions, the beam 30 reflected from the mirror 42 passes successively into the collimators 35 and 37, by which it is transmitted to light-sensitive cells or relays represented here by photoelectric cells 31 and 32. Similarly the beam 52 is reflected into the collimators 38 and 40, and by them transmitted to the cells 33 and 34.

The facets of the mirror 42, the imaging lenses 36 and 39, and the collimating lenses 35 and 37, 38 and 40, lie in the angular relation shown in Fig. 7, whereby when the mirror 42 is rotating in proper synchronism with the rod 15, the flashes of radiation entering cells 31 and 32 are separated by equal intervals from the flashes which enter the cells 33 and 34. The position on the curve 132 representing the vibratory motion of the rod at which occur the momentary flashes which enter the several photoelectric cells are shown in Fig. 13, where the succession of points 140, 141, 142, 143, 144, 145 represent the portions of the beam 30 (Fig. 1) which enter the cells 31 (Fig. 1), and the points 141 represent the portions of the beam 30 (Fig. 1) which enter the cell 32 (Fig. 1). Likewise the points 142 and 143 respectively represent the

portions of the beam 52 (Fig. 1) which enter the cells 33 and 34 (Fig. 1) respectively.

In order to make clear the method by which these momentary flashes of light from selected epochs of the vibration of the rod are utilized to control the driving energy of the rod, it will be useful first to simplify the conditions and to consider the action of a single one of these series of momentary radiation pulses. Such a series, equivalent to the series 141 of Fig. 13 is shown at 141 in Fig. 10. It will be noted that when these points are located on the axis 133, the light transmitted is circularly polarized, as shown on the arbitrary scale of retardations at the left of this figure. If, however, the series be slightly shifted along the time axis in either direction, these selected points at which light is reflected by the rotating mirror into the corresponding photoelectric cells will move into regions of different polarization, as shown at 141', where the retardation is plus 1, and at 141'', where the retardation is minus 1. Such a shift along the time axis would be caused by a departure from synchronism of the rotating mirror 42 with reference to the vibrations of the rod 15.

In Fig. 11 are shown two series of points 140 and 141 at which determinations of strain in the rod are made, the phase position of the two series of points being that which they occupy when the driving current and the rod are in synchronism. If now these two series of determinations be shifted slightly along the time axis as shown in Fig. 12, which corresponds to a lag of the rotating mirror, the series 140 will acquire retardations corresponding, for example, to the point 145 of Fig. 15, and the series 141 will acquire retardations corresponding to the point 145' of Fig. 15. That is, the light in the one series will be polarized in a vertical plane, and in the other series the light will be polarized in a horizontal plane, as shown at 156 and 156', respectively. Consequently the light representing the series 140 will be completely extinguished in the analyzer 26 (Fig. 1) and the light representing the series 141 will be completely transmitted by the analyzer 26 and will proceed on to the photoelectric cell 32. It is thus plain that a movement of the two series of points 140 and 141 along the time axis in either direction due to a departure from synchronism of the rotating mirror 42 will cause a differential change in the quantity of radiation that enters the two photoelectric cells 31 and 32. This differential change, the sign of which is fixed by the direction of displacement, is utilized to correct the rate of rotation or phase position of the rotating mirror 42, and simultaneously to correct the phase relation of the driving electromotive force to the vibrations of the oscillator, the correction in question depending on the establishment of a photometric balance between the photoelectric cells concerned in the reception of the light impulses.

Referring again to Fig. 1, the oscillating rod 15 is shown as bearing conducting plates or armatures 16, in close apposition to which are held electrodes 17. The rod 15 is supported at 19, which serves as the nodal point of oscillation, and the field plates 17 are supported in correct relation to the armatures 16, by means shown in detail in my foregoing application on electromechanical oscillators above referred to. The armatures 16 are connected by conducting leads 18 and 20 to one terminal of the battery 28. The field plates 17 are connected by leads 29 and 53 through the secondary winding 112 of the mutual

inductance coil 111 and the lead 54 to the other terminal of the battery 28, the purpose of which battery is to hold the opposed plates 16 and 17 under a certain electrical bias. On an oscillating potential being developed in the coil 112, attractions and repulsions are set up between the opposed plates 16 and 17, which serve to drive the oscillator in a way detailed in my above mentioned application. It will be noted that the oscillator 15 comprises two aliquot portions 55 and 56, each of which portions may be considered as a separate oscillating member in that the oscillation of each portion is determined by its own physical characteristics and by the node-fixing action of the clamp or support 19. It is a feature of the present invention that energy may be supplied through the electrodes 16 and 17 to each of these aliquot portions 55 and 56.

This oscillating electromotive force, which with the apparatus to be described can be made to be of substantially sinusoidal character, is generated in the secondary 112 of the transformer 111 through energy supplied by the alternator 114 which may consist of a conventional construction shown in end elevation and in greater detail in Fig. 3, where a rotating field 106 consisting of a permanently magnetized bar or its equivalent is mounted on and driven by the shaft 104, and the stator coils 107 are mounted on the turntable 121, by rotating which last the angular position of the stator coils with respect to the field piece or rotor may be changed and the phase relation of the resulting current to the phases of the rotation of the field piece and other parts connected to the rotor shaft, that is, the phase coupling between the alternator and the oscillator, adjusted. As the rotor 106 turns, its north and its south pole pass before successive pairs of the stator windings 107, generating an alternating E. M. F. in the latter. The stator coils 107 are connected through leads 108 to the primary winding 109 (Fig. 1) of the mutual inductance coil or transformer 111.

The alternator 114 is driven by a motor 101, which derives its energy from the current source 102. A variable resistance 103 is provided by which the input of energy to the motor 101 may be adjusted. Mounted on the shaft 104 of the motor 101 are, besides the rotor 106 above mentioned, the multiple-faced mirror 42 and the braking disk 105. Together, these comprise the rotating inertial system designated generally at 115. It will be noted that the mirror 42 is shown at two positions in Fig. 1, being shown in axial view in the upper part of the figure and in plan view in the lower part of the figure. This duplication was made necessary by considerations of clearness in the diagram.

The electrical and mechanical system shown as enclosed by the brace 62 represents an application of synchronizing and governing apparatus described in detail in my copending application on Apparatus for synchronizing electromechanical system filed April 22, 1929, Serial Number 357,163, and my copending application representing a continuation in part of the above application, bearing the same caption and filed May 13, 1929, Serial Number 362,811. The operation of the above apparatus in its present application will now be described.

Considering first the function of the photoelectric cells 31 and 32, it will be noted that these cells are connected in series, the cathode 48 of the cell 31 being connected by the lead 43 to the negative terminal of the battery 44, and the an-

ode 49 of the cell 31 to the cathode 50 of the cell 32, the anode 51 being connected through the lead 45 with the positive terminal of the battery 44.

5 With radiation of equal intensity entering the photoelectric cells 31 and 32, which will be the condition when proper synchronism is maintained, there will be an equal flow of current through the two cells, and due to the fact that 80
 10 the intermittent beam will be integrated in the cells due to the electrical capacity of the electrical elements comprising the lead 46 and the parts connected by it, the lead 46 will be held at a given negative potential. Suppose now that 85
 15 due to a shift of the mirror 42 from synchronism, the luminous flux active in the two cells is differentially varied, so that a greater amount of luminous flux enters cell 32 and a smaller amount of flux enters cell 31. The current flow 90
 20 through 31 is decreased and the flow through 32 is increased, resulting in a lower negative potential active in the lead 46. Conversely, the opposite condition of relative illumination results 95
 25 in a higher potential in the lead 46.
 30 The potential active in the lead 46 controls the output of the amplifier comprised in the brace 61, which may consist of a conventional grouping such as the four-electrode thermionic vacuum tube 64, including a filament 68 heated by 100
 35 a battery 69, an accelerating grid 67 held at a certain positive potential by the battery 70, a shielding grid 65 which connects with the lead 46, and the anode plate 66, held at a certain positive potential with respect to the filament 68 by the source of E. M. F. 71. A high resistance 72 serves as a conducting link between the plate and 105
 the filament leads.

The output of the four-electrode tube 64 is amplified by the three-electrode tube 73, whose grid 75 has connection in the plate circuit of the tube 64, as shown. The output circuit of the tube 73 comprises the plate 74, one of the energizing coils 80 of the compound-wound braking electromagnet 81, the current source 79, and the primary coil 78 of the mutual inductance coil or transformer 90.

The secondary coil 91 of the transformer 90 is connected across the filament 88 and the grid 87 of the amplifier 85. A biasing battery 77 maintains the grid 87 of the tube 85 at a potential such that, with no other electromotive force active in the filament-grid circuit of this tube, the value of the plate current corresponds approximately to the mid-point of the grid-potential plate-current curve of the tube. The filament-plate circuit of the tube 85 includes the current source 84, and the second magnetizing coil 83 of the compound-wound electromagnet 81. The coils 80 and 83 are so connected in their respective 115
 55 circuits that the normal continuous flow of current through these coils results in an additive magnetic field of like sign being generated in the common core 82 of the two coils.

The conducting disk 105, which is rotated by 60 the motor 101 in the magnetic field of the electromagnet 81 has a retarding or braking force brought to act in it through the eddy currents generated in the disk 105 as it moves through the magnetic field of the electromagnet 81. The variable resistance 103 is so adjusted that the input of energy to the motor 101 is in amount such that with equal illumination of the cells 31 and 32, and with a resulting median current flowing in the output of the amplifier 61, the braking 120
 65 action exerted by the electromagnet 81 is just 125
 70 sufficient to balance the frictional forces of the motor at synchronizing speed.

As above detailed, the potential active in the lead 46 acts through the amplifier 61 to control the current flow through the output circuit of the amplifier 61, and it will be plain from considerations developed above that the value of the output current is greater for an angular lead of the mirror 42 and less for an angular lag of the mirror 42. Consequently the current flow in the magnetizing coil 89 of the electromagnet 81, the magnetic flux cut by the disk 105, and the braking force acting to slow down the rotating system 115, which includes the multifaced mirror 42, are all in the same sense greater for a lead of the mirror 42 and less for a lag of the mirror 42. In other words, when the system is in such relation that the series of points of strain determination 140 and 141 are as shown in Fig. 11, the braking force has a median or normal value, when the series of points occupy the position shown in Fig. 12, the braking force has a lower value, and when the series of points are displaced along the time axis in a direction opposite to that shown in Fig. 12, the braking force has a higher value. This 130
 75 action of the rotating system in which a force (represented by the driving force of the motor) is applied, tending to cause the moving system to depart from synchronism by taking on a faster rate of movement, and a second force (represented by the braking force exerted on the disk 105) is applied, tending to cause the moving system to depart from synchronism by taking on a slower rate of movement, the value of the latter force being automatically controlled, tends to hold this system in synchronism with the rod vibrations, and to hold the driving energy in the relation shown in Fig. 9. (The term synchronism is used here as implying that the periods of the various phenomena concerned are either the same, or are simple multiples or submultiples of each other, though not necessarily that there is phase coincidence between any of these phenomena.)

It may be stated here that the synchronous speed of the rotating system 115 including the mirror 42 will depend on the number of facets in the mirror 42, each facet corresponding to a complete oscillation, and that the number of stator coils 107 in the alternator 114 will be determined by the number of facets in the mirror 42.

It is a well known fact that where an inertial system such as the rotating system 115 of the motor 101 is subjected by a stabilizing apparatus to a correcting force tending to return it to a certain desired fiducial position, such as a position corresponding to a given phase relation or to a position of equilibrium, the impetus given the inertial system in the process of returning it to the desired position causes the inertial system to pass beyond this position. In this second position of displacement the inertial system is again acted on by a correcting force tending to return it to the normal position. It again acquires kinetic energy and is again carried beyond the desired position, and this action continues. This oscillation of the inertial system over a certain amplitude on either side of the correct position, known as "hunting" may in certain applications be very persistent and objectionable.

In the present invention hunting of the local 140
 80 system is obviated by an application of methods developed at length in my two applications for patent on synchronizing apparatus, above referred to, in which apparatus means are provided whereby the force resisting a displacement of the 145
 85 90 95 100 105 110 115 120 125 130 135 140 145 150

inertial system from the correct phasal position is of many times the value of the force tending to return the system to this position. Any overshooting of the inertial system due to accumulated kinetic energy is rapidly arrested, and, when the inertial system is brought to a halt, a much smaller force acts to return the system to the normal phase position, and hence the kinetic energy accumulated during the movement of return is correspondingly smaller. The oscillations of the inertial system in establishing an adjustment thus possess a very steep decrement, however large the forces applied in maintaining an adjustment, and the synchronized system maintains a correspondingly close phasal relation with the system to which it is synchronized.

The components particularly involved in the device for preventing hunting are the transformer 90, the amplifier 85, the current source 84, and the coil 83 of the compound wound electromagnet 81.

In following the correcting action of this system of elements, assume that the rod vibrations and the mirror revolutions are in proper synchronism. A substantially constant current of some certain value is thus flowing through the winding 78 of the mutual inductance coil 90 and the winding 80 of the braking electromagnet 81. No induced current is flowing in the secondary 91 of the transformer 90; a certain median current is hence flowing through the coil 83, which acts with that flowing in the coil 80 to produce a certain flux in the braking electromagnet 81, resulting in a speed of the motor 101 which results in proper synchronism.

Assume now that through some transient cause the rotating inertial system 115 of the motor 101 is slightly retarded. A smaller current flows through the output of the amplifier 61, decreasing the flux in the braking coil 80, and the motor rotating system 11 tends to increase its speed and to take up a position of advance. Simultaneously with the departure from the correct phasal position there is a drop in the value of current flowing in the primary winding 78 of the transformer 90, and an E. M. F. is induced in the secondary 91 of the latter. The connection of the secondary winding 91 with the filament 88 and the grid 87 of the tube 85 is such that this induced E. M. F. acts to reinforce the E. M. F. of the biasing battery 77 and thus to decrease the normal flow of current through the output of the tube 85, as also through the coil 83, and to reduce the braking action exerted on the disk 105. In other words, the altered flow of current in coils 80 and 83 caused during the period of retardation of the inertial system 115 acts individually and additively to prevent further retardation or departure from the normal phase position.

As soon as the motion of departure has been halted, however, no further change occurs in the density of current flowing in the primary 78 of the transformer 90, the E. M. F. generated in its secondary 91 falls to zero, and the current flowing through coil 83 regains its normal value. However, the current flowing in coil 80 still has a lower value than the normal value, due to the lag from the correct phase relation, and the reduced braking action tends to cause the system to begin a motion of correction toward its normal phase position. As soon as this motion of recovery begins, the current flowing in the output circuit of the amplifier 61, which includes the coil 80 and the primary 78 of the transformer 90, increases, and an E. M. F. is induced in the sec-

ondary 91 of the transformer 90, the polarity of which E. M. F. is opposite to the polarity of the E. M. F. which had been induced during the motion of departure. The biasing action of the battery 77 is hence in this case opposed, and more than the normal current is allowed to flow through the coil 83. The action of the coil 80 tending to return the rotating system to the desired phase position is thus opposed and partially balanced out, and this restraining action of the coil 83 on the coil 80 continues throughout the period of return to the normal or fiducial position. The motion of recovery must therefore take place slowly as compared with the motion of departure.

From the above it is seen that, during the period of retardation of the rotating mirror due to the action of a disturbing force, the coil 83 acts to assist the coil 80 in preventing the retardation, but during the period of recovery the coil 83 acts to resist the action of the coil 80. In other words, the force opposing a departure from the normal phase position, when that departure is in the direction of a retardation of the rotating system 115, is much greater than the force tending to return the system to the normal phase position.

An analogous action takes place when the departure is in the direction of an advance from the normal position. During the period of departure the current flow in the output of the amplifier 61 increases and that portion of the braking effect caused by the flux generated by the coil 80 is likewise increased. Coincidently with the departure, an E. M. F. is induced in the secondary 91 of the transformer 90 which tends to oppose the E. M. F. of the biasing battery 77; the current in the coil 83 is thus also increased. The coil 80 and 83 thus both act during the period of departure from the correct phase position to prevent the motion of departure. When the departure ceases, the current in coil 83 returns to its normal value, whereas the current in the coil 80 remains at a higher value than normally, and tends to increase the braking of the disk 105 and so to bring the system 115 back to its normal phase position. As soon as the motion of return toward the correct phase position commences, however, the current in the circuit including the coil 78 decreases, an E. M. F. is generated in the coil 91 which assists the biasing action of the battery 77, and the current in the coil 83 of the braking electromagnet 81 is decreased.

From the above it is clear that when a departure from synchronism consisting either of a lead or a lag from the desired phase relation occurs, the braking electromagnet coils 80 and 83, which control independently variable components of the correcting force, assist each other during the period of departure and oppose each other during the period of recovery. This is a condition conducive to great stability in the rotating system, and the latter will hence suffer displacements through only a very small angle on either side of the desired phase position. When the azimuth of the field coil turntable 121 (Fig. 3) has been adjusted to such an angular position with respect to the facets of the mirror 42 that the phase relation of driving force and oscillator vibrations are as shown in Fig. 9, the apparatus thus far detailed will operate to maintain this phase relation as long as the oscillator is in operation.

In order to ensure that the decrement in the oscillating rod remains constant it is necessary that the amplitude of vibration of the rod be held

constant, regardless of external conditions or changes in the constants of the driving circuit. In the present invention this is accomplished through optical means closely analogous to those just described in connection with the control of the phase position of the driving force. The series of strain determinations here concerned are those shown at 142 and 143 of Fig. 13, and occur, as will be seen, at opposite crests of the vibrations. Selections from the light beam 52 are made at these points by the mirror 42, as above detailed. In the illustrative construction shown, light from the series 142 enters the cell 33 and light from the series 143 enters the cell 34. In the normal operation of the oscillator, the light at the terminal crests of the vibrations is circularly polarized, as shown at 155 and 155' in Fig. 15. The cells 33 and 34 are thus normally equally irradiated, the lead 47 is held at a given potential, and the current output of the amplifier 63, whose construction is similar to that of the amplifier 61, is held at a given level. If the amplitude of the rod be assumed to fall to the point 162, 162' of Fig. 15, corresponding to radiation of the character indicated at 160, 160', respectively, more radiation enters the cell 33, less radiation enters the cell 34, the potential of the lead 47 is lowered, and the current output of the amplifier 63 is lowered. The converse action takes place if the amplitude of the rod is increased.

The current output of the amplifier 63 passes into coil 110, which constitutes a separate winding on the transformer 111. As above stated, the alternating current produced by the dynamo stator coils 107 flows through the primary winding 109 of the transformer 111, producing an alternating change in magnetic flux in the core 113, the result being the generation of an alternating potential in the secondary coil 112, which acts harmonically on the electrodes 16 and 17 to drive the oscillator.

The effect of the variation of current in the coil 110 on the potential of the alternating current supplied to the driving electrodes 16 and 17, on which depends the amount of driving energy supplied to the rod 15, will be made apparent by an inspection of the diagram, Fig. 16, which represents the saturation curve of a sample of low carbon silicon iron, such as might constitute the core 113 of the transformer 111, (Fig. 1), the magnetic flux density being plotted as ordinates against the exciting current.

Assume that the greatest value of current that can be passed by the amplifier 63 (Fig. 1) and delivered to the winding 110 to be that shown at 180 (Fig. 16), which suffices to raise the saturation curve of the core 113, (Fig. 1), to the point 170, (Fig. 16). Assume also that the normal working point of the amplifier 63 (Fig. 1) is the point 179 (Fig. 16), and that this point of saturation is, normally, continuously maintained by the action of light reaching the photoelectric cells 33 and 34, (Fig. 1).

Assume further that the sinusoidal current flowing in the coil 109 (Fig. 1) represented by 175 (Fig. 16) superposes a magnetic change of flux density comprised between the abscissae 173, 174 on the normal magnetization due to the current flowing in the coil 110. This will then lead to the generation of an alternating E. M. F. in the secondary 112 having a certain value. If now an increase of current in the coil 110 due to an increase of amplitude in the rod vibrations lift the level of saturation in the core 113 (Fig. 1) to the point 181 (Fig. 16) then the cyclic differ-

ence of saturation due to the periodically fluctuating current 175' flowing in the coil 109 (Fig. 1) will have fallen to the value comprised between the abscissae 171, 172 (Fig. 11) and the potential of the alternating driving current in the secondary 112 (Fig. 1) and consequently the driving effect on the rod, will have fallen to a correspondingly smaller value. Conversely a decrease of current in the coil 110 (Fig. 1) caused by a fall in amplitude, will have the effect of increasing the driving E. M. F. produced in the secondary 112. In either case the departure of the rod from the correct amplitude is corrected.

It will be of advantage from the point of view of sensitiveness that the iron of which the core 113 Fig. 1 is constituted be of a kind such that the break in the curve of saturation is rather abrupt, and that the amplifier 63 have a fairly steep characteristic.

The amplitude of beat of the rod can be changed after the rod has been set in motion from one value to another to suit a predetermined or desired value by adjusting the compensator 24 (Fig. 1).

Since the inertia of the entire optical and electrical system of correction in the amplitude governor just described is very small as compared to that of the oscillating rod, and since the energy supplied to the rod in returning it to a given position of amplitude will not tend to take it beyond that position, there will be a total absence of hunting. The effect on amplitude caused by the very small departures from synchronism that may take place in the rotating mirror 42, which departures must for reasons above explained necessarily be confined within the region separating two areas of oppositely plane polarized light, and will practically be confined to a small portion of such a change, will have only an infinitesimal effect on the amplitude, for the change of phase effects in the polarized radiation for a given displacement on the time axis is smallest at the crests of the vibrations, represented by the points 142 and 143 on the curve 132, Fig. 13, and greatest at the points 140 and 141 at which this curve cuts the axis of abscissae.

The totality of apparatus above described, in short, acts to control the motive parameters of the driving force (i. e., both the phase relation of this force to the oscillator vibrations and its effective intensity as a driving agency) by means which do not in any way depend on a coupling involving an exchange of energy between the oscillator and the governing apparatus which controls these motive parameters.

In "starting" the oscillator, or initiating its vibration, the rotating system 115 is allowed to gain speed from a position of rest until the electrical oscillations produced in the coil 112 comes to consonance with the natural period of the rod, when the latter will begin to oscillate, and the rotating system will be held automatically in a position of synchronism.

While I have described my invention in detail with respect to the preferred form thereof, I reserve the right to make such changes in the details of construction or such substitution of equivalents as conform to the spirit of the invention or fall within its scope as defined in the appended claims. It is moreover not indispensable that all features of the invention be used conjointly, as they may be advantageously employed in various combinations or subcombinations.

I claim:

1. A body capable of oscillation, means for applying a motive force to cause said body to oscillate, means controlled by said body to vary 5 the characteristics of a beam of radiation according to the phase position of said oscillator, and means by which radiation corresponding to certain phases of oscillation of said body control motive characteristics of the applied force.
- 10 2. An oscillator, means to supply a periodic driving force to said oscillator, optical means for determining the momentary phasal positions of said oscillator, and means responsive to the value of said determinations to control the phase relation of said driving force.
- 15 3. A transparent oscillator, means for supplying driving energy to said oscillator, means for passing radiation through said oscillator, and means responsive to changes in the character of 20 said radiation caused by the oscillation of the oscillator to control said driving energy.
- 25 4. An oscillator, means for applying driving energy to said oscillator, generating means for producing said driving energy, and means controlled by said oscillator and active on said generating means to vary the phase relation of the oscillations of said oscillator to the cycles of said driving energy.
- 30 5. A body capable of oscillation, means for generating a driving force to cause said body to oscillate, said generating means including an inertial system moving substantially in synchronism with said body, means for determining momentary phase positions of said body, and 35 means responsive to said determinations to control the movement of said inertial system.
6. In a periodic system comprising an oscillator and a moving inertial system normally held in substantial synchronism with said oscillator, the improvement characterized by means for applying a force tending to cause said moving system to depart from synchronism by taking on a faster rate of movement, means for applying a second force tending to cause said inertial system to depart from synchronism by taking on a slower rate of movement, and means controlled by said oscillator to vary one of said forces to maintain said moving inertial system in substantial synchronism with said oscillator. 80
7. A transparent oscillator, means for passing a beam of polarized light through said oscillator, optical analyzing means to extinguish said polarized light as a function of the phase position of said oscillator, receptors to convert the energy of said light into electrical energy, means to direct said light into said receptors according to the phases of said oscillator, means to generate energy to drive said oscillator, and means associated with said receptors to control said energy generating means. 90
8. The method of controlling the oscillation of 100 a mechanical oscillator which consists in generating electrical oscillations, producing mechanical oscillations by means of said electrical oscillations, altering a stream of radiation by means of said mechanical oscillations, and controlling the 105 characteristics of said electrical oscillations by means of said altered stream of radiation. 95
